GRINDER MACHINE

Emil F. Hager, Queens Village, N. Y.

Application February 2, 1945, Serial No. 575,749

16 Claims. (Cl. 51—125)

1

This invention relates to work grinding and dressing machines and more particularly to a machine having a spindle for driving a pair of grinding and dressing elements, and a support for holding a tool or other work at desired angles for movement relative to said elements.

It has been the practice heretofore to provide a work support adjustable along a guide bar disposed parallel to the spindle but closely adjacent the grinding and dressing elements carried by the spindle. This bar, in order to resist wear and abrasion from the cuttings produced by the grinding and dressing operations, must be specially hardened and trued at considerable expense.

It is an object of this invention to provide a work shaping machine of a construction such that the bar required to guide the work support need not be specially hardened.

Another object of the invention is to provide an improved grinding and dressing machine having a work support guiding bar disposed outside the zone of flying particles produced by the grinding and dressing operations.

Still another object of the invention is to provide an improved work support for grinding and dressing machines capable of various angular adjustments and/or movements.

A further object of the invention includes the provision of a special mount for the grinding and dressing elements so that the hub of the spindle does not protrude out beyond the radial working face of the wheels; an easily removable guard for the grinding and lapping wheels; and a bearing arrangement for the spindle which is easily adjusted to remove end play.

The above and other objects of the invention will become more clearly understood from the following detailed description to be read in connection with the accompanying drawings in which:

Fig. 1 is a plan view of a work grinding and dressing machine according to this invention;

Fig. 2 is a fragmentary view in front elevation with parts in section of the grinder machine showing the work support adjacent one of the grinder elements;

Fig. 3 is a sectional view taken substantially along line 3—3 of Fig. 1;

Fig. 4 is a cross sectional view taken substantially along line 4—4 of Fig. 3;

Fig. 5 is a cross sectional view of a modified track structure for the work support; and

Fig. 6 is a view in side elevation of a work supporting table.

2

Referring to Figs. 1, 2 and 3 of the drawings a base 1 is shown with an opening 2 defined by a flange 3 upon which is mounted a grinder head 4. The head 4 includes a hollow stand 5 having bearings such as indicated at 6 to support a spindle 7. Each bearing is held in position by a clamp 8, Fig. 3, which when loosened permits the taking up of slack in the bearings 6, the clamp thereafter being tightened. The spindle 7 supports for rotation, grinding and dressing wheel elements 9 and 9a preferably of the character having working surfaces on the sides thereof. Each wheel element is partially covered with a guard 10. A liquid circulating system 11 directs cooling and cleaning liquid onto the working surfaces 12 of each of the elements 9 and 9a.

The base 1 includes an upturned marginal flange 13 to provide a catch basin for the liquid and cuttings during grinding and dressing operations, the liquid and cuttings being removed by drain 14. Mounted outside the basin on arms 15 is a guiding bar 16 for a carriage 17 which supports a work holding post 18. The carriage is adjustable along the bar 16 and may be locked thereto in any desirable position by means of locking screw 19.

The bar 16 is disposed parallel to the spindle 7. The frame of the carriage 17 is triangular as viewed in plan, Fig. 1, and two corners thereof are provided with bearing elements 20 and 21 which receive the bar 16 to guide the carriage along a true line parallel to the spindle 7. Toward the apex of the carriage is a depending leg 22 provided with a roller 23 which tracks upon a machined surface 24 on the base 1.

If desired, the track surface 24 may be raised as indicated at 25, Fig. 5. The roller 23 may also be replaced by sliding surfaces such as provided by the rod 26 and the curved foot member 27. Still other movable supporting and track arrangements may, of course, be employed.

As shown in Fig. 4 the apex of the carriage 17 is provided with two spaced support elements 28 and 29 onto which a rock member 30 is mounted for rocking and sliding movements as more particularly described hereinafter. The rock member in turn pivotally supports a post 31. The post 31 is preferably supported with its longitudinal axis disposed transverse to the axis of the rock member 30. The member 30 is provided with a tubular socket 32 for reception of the lower end of the post 31, the post being locked in position by lock screw 33. On the socket 32 is keyed a calibrated dial 34 over which is disposed a pointer 35 keyed to the post 31. This provides

an angular indication of the adjusted position of the post 31.

The upper end of the post 31 is provided with a transverse opening 36 for receiving a pin 37 on which a work supporting clamp 38 is mounted. The pin 37 is secured in the opening 36 by a key 39. A calibrated dial 40 is in turn keyed to the pin 37, the table of the clamp being provided with a mark to determine the angular position of the clamp with respect to the longitudinal axis of the post 31. The table of the clamp is provided with two legs 41 and 42 which straddle the end of the post 31, the leg 42 being provided with a lock screw 43 for securing the clamp in the desired angular position.

From the foregoing description it is clear that the post 31 may be adjusted to any desired angular position about its longitudinal axis and the clamp 38 may be adjustable about an axis transverse to the longitudinal axis of the post 31. It will now be described how the post is made adjustable along an axis transverse to the longitudinal axis, or in other words, parallel to the axis of the spindle 7. It will also be described how this mounting provides for rocking movement of the post 31 toward and away from the spindle 7 so as to provide movement of the work being shaped relative to the surface 12 of the grinding element 9.

As shown in Fig. 4 a trunnion sleeve 45 is held by screw 49b in support element 28 with a pusher pin 46 extending therethrough. The member 30 is locked to the trunnion 45 by a lock screw 47. A second trunnion 48 is held in position in the element 29 by a set screw 49a, Fig. 3. Disposed in the trunnion 48 is a retraction spring 49 the outer end of which carries a thrust pin 50. Mounted in opposite ends of the member 30 are two thrust caps 51 and 52 having thrust points engaging pusher rod 46 and thrust pin 50 respectively. The inner end of the pusher rod 46 is engaged by a pin 53 held by crank 54 (see Fig. 3) carried by shaft 55. A second crank arm 56 is secured to the shaft 55 which is engaged by a connecting pin 57 controlled by adjustment screw 58. This screw is preferably provided with calibrations by which the extent of adjustments can be readily determined with respect to a stationary pin disposed closely adjacent thereto.

By adjusting the screw 58 the crank arm 56 is forced to the right as viewed in Figs. 2 and 4 thereby causing the pin 53 to actuate pusher rod 46 to the right. The pusher rod carries with it the member 30 thereby moving the post in a direction parallel to the axis of the spindle 7. This movement of the member 30 compresses spring 49. Retraction of the adjustment screw 58 permits the spring 49 to return the member 30 to the left maintaining the pusher rod 46 against the pin 53. It will thus be apparent that by adjusting the screw 58 forward and backward the member 30 is moved lengthwise of trunnions 45 and 48, relative to the carriage 17.

The rock member 30 when unlocked by releasing lock screw 47 is rotatable about the trunnions 45 and 48. This provides spaced bearing surfaces at 60, 60a for the member 30 thereby enabling the operator to rock the member 30 and the work supporting post 31 carried thereby about the axis of the trunnions 45, 48. In order to limit the rocking movement of the member 30 the member is provided with a stop lug 61 secured thereto by lock screw 62, the lug 61 being engageable with a stop pin 63 adjustably supported by set screw 64 on a projection 65 of the carriage 17.

The adjustment provisions for post 31 and clamp 38 permit the positioning of the work such as tools at various predetermined angles relative to the surfaces 12 of the work shaping elements 9 and 9a. By manipulating adjustment screw 58, the work may be moved into the cutting surface 12 while rocking the work to and fro across the face of the surface 12.

In Fig. 6 I show a work supporting table 38a which may be substituted for the work supporting clamp 38, the table being adjustable to desired angles for free hand grinding and lapping operations. The base portions of the clamp and the table are identical as indicated by the like reference characters applied thereto in Figs. 3 and 6 respectively.

Another feature of the invention is the unique mounting arrangement for the grinding and lapping wheels. As shown in Fig. 2 the wheel 9a is supported on a flanged collar 66 the inner edge of which is urged against the bearing assembly 6. The collar has a radially extended flange 67 having threaded openings 68 for reception of the threaded portions of bolts 69. The collar is held upon the spindle 7 by a circular nutlike element 70 threadably received on the threaded end 71 of the spindle. The wheel 9 or 9a, as the case may be, is received on the collar against the flange 67. The wheel is provided with openings 30 aligned with openings 68 for reception of bolts 69. A ring 72 is provided with openings also aligned with openings 68 for reception of bolt 69 whereby the wheel is tightly secured in position. By this arrangement the wheel is supported at the very 35 end of the spindle without appreciable extension beyond the plane of the radial working face 12 of the wheel. This arrangement also provides for quick removal and replacement of wheels without changing the position of the collar 66 and nut 70 or altering the end play adjustment of bearing 40 arrangement 6.

As previously stated the outer housing 73 of the bearing 6 is engaged and held in position within the grinder head by clamp 8. The spindle 7 is provided with a shoulder 74 against which the inner ball bearing race 75 is held by sleeve 76, collar 66 and nut 70. The outer race 77 is held by the housing 73 to which packing ring 79 is threaded. It will be clear that any end play in 50 the ball bearing arrangement may be removed by loosening the clamp 8 at 78, Fig. 3, and urging the ring 79 and housing 73 to the right as viewed in Fig. 2. This forces the outer race 77 to the right relative to inner race 75 which abuts against shoulder 74. Since the bearings at the opposite 55 ends of spindle 7 are identical, objectionable end play in both bearings is removed by this one operation, the clamp on the opposite bearing being maintained in tight position so that the force acting through spindle 7 also tightens the opposite bearing at the same time. The loosened clamp 8, of course, is tightened while the bearings are thus urged into the desired relation. Once this 60 adjustment is made, removal and replacement of the wheels 9 and 9a will not alter the adjustment, since as is easily seen, the wheel mounts are independent of the bearing assemblies.

The guard 10, according to this invention, may be provided with straight sidewalls which cover substantially all of the wheel except for a small portion at the front side of the grinder. The guard is secured on the grinder head by two bolts 80, Fig. 2, and 81, Fig. 3. When these bolts are removed the guard may be removed or lifted from 75 the wheel. This enables the guard to be easily

replaced by other guards such as those more fully open in front for use in conjunction with radius lapping attachments, for example.

Attention is called to the fact that the grinder head comprises a minimum of parts easily assembled and adjusted. The standard 5 is cast in one piece and the bore for the bearings 6 and spindle 7 is machined in one operation. The clamps 8 are positioned in the standard before the spindle and bearings are inserted in the bore. After the wheels 9 and 9a are mounted on the spindle, the guards 10 are secured in position together with the tubes of the liquid circulating system.

While I have shown and described the principles of my invention in connection with specific apparatus it will be understood that such specific showing is intended to be illustrative of the invention only and not as limiting the scope of the invention as set forth in the objects and the appended claims.

I claim:

1. In a work shaping apparatus having a spindle and work shaping means carried by said spindle, a bar disposed parallel to said spindle, a carriage mounted at least in part on said bar for movement in directions parallel to said spindle, a member carried by said carriage with a given axis thereof disposed at an angle to the axis of said spindle, means on said carriage for moving said member relative to said carriage in directions parallel to said spindle, means for pivotally adjusting said member about said given axis, a work supporting means carried by said member, and means for pivotally adjusting said work supporting means about an axis transverse to said given axis.

2. In a work shaping apparatus having a spindle and work shaping means carried by the spindle, a carriage, means for moving said carriage for coarse adjustment parallel to said spindle, a work supporting member on said carriage, a lever pivoted on said carriage and a threaded element to actuate said lever to move said member for fine adjustment relative to said carriage and in a direction also parallel to said spindle, and a pivoted support for rockably supporting said member on said carriage about an axis parallel to said spindle.

3. In a work shaping apparatus having a grinder head provided with a spindle and at least one grinder wheel, and means to apply liquid to said wheel, a base disposed below said grinder head and having an upturned marginal flange to catch liquid and cuttings during grinder operations, a carriage, a bar horizontally disposed outside the confines of said flange, means providing a track within said marginal flange, and said carriage having means for engaging said bar and said track to guide and support said carriage for movement in direction parallel to said spindle.

4. In a work shaping apparatus having a grinder head provided with a spindle and at least one grinder wheel, a base disposed below said grinder head, said base having an upturned marginal flange to form a basin, a carriage, a bar horizontally disposed outside the confines of said flange for guiding said carriage for movement in directions parallel to said spindle, and means providing a track on said base within the confines of said flange, and means on said carriage for engaging said bar and said track.

5. An apparatus according to claim 4 further including a work supporting post, means on said carriage pivotally supporting said post for move-

ment about an axis transverse of said spindle, and means for moving said work supporting post relative to said carriage along an axis parallel to said spindle.

6. In work shaping apparatus having a grinder head provided with a spindle and at least one grinder wheel, a base disposed below said grinder head, said base having an upturned flange to form a basin, a bar disposed along one side of said basin, means providing a track in said basin parallel to said rod, a carriage for movement parallel to said spindle, said carriage having two spaced bearing elements receivable on said bar to guide said carriage and a third bearing element adapted to engage said track, means to lock said carriage in desired locations along said bar, a work supporting post, said carriage having a rock member thereon to support said post, and means on said carriage for adjusting said rock member lengthwise of the axis thereof.

7. In work shaping apparatus having a grinder head, a base disposed below said grinder head, said base having an upturned flange to form a basin, a bar horizontally disposed adjacent a part of said upturned flange, means providing a track in said basin parallel to said bar, a carriage, and means to support and guide said carriage on said bar and said track.

8. Apparatus according to claim 7, wherein said bar is located on said base beyond said upturned flange so that the carriage overlies said flange between said bar and said track.

9. Apparatus according to claim 7, wherein said track comprises a bar mounted within said basin and said carriage includes a bearing element adapted to engage the bar of said track.

10. A work support comprising a base having a pair of spaced support elements, a hollow trunnion carried by each of said elements, a rod extending through one of said trunnions, a spring disposed in the other of said trunnions, a rock member carried by said trunnions for rocking movement thereon, thrust elements carried by said rock member, one to engage said rod and the other to engage said spring in opposed directions, and means for moving said rod to adjust said rock member lengthwise of said trunnions, said spring operating to hold said member against said rod.

11. A work support comprising a base having a pair of hollow trunnions, a rock member carried by said trunnions for rocking movement thereon, a rod extending through one of said trunnions for engagement with said rock member, a spring disposed in the other of said trunnions to urge said member against said rod, and means for moving said rod to adjust said rock member lengthwise of said trunnions.

12. A work support according to claim 11 and means adjustable to limit the rocking movement of said rock member.

13. A work support according to claim 11 wherein said means for moving said rod includes a leverage arrangement and an adjustment screw by which fine adjustment is obtainable.

14. A work support according to claim 11 wherein said adjustment screw is provided with calibrations and said base is provided with a pin disposed closely adjacent to said screw to provide a reference point for determination of the extent of the adjustment.

15. In a work shaping apparatus having a spindle and a work shaping means carried by said spindle, a carriage movable in a direction parallel to the axis of said spindle, a rock member,

bearing means on said carriage to support said member for rocking movement, means to effect adjustment of said rock member lengthwise of its bearing support, a post, said rock member having a socket for pivotally supporting said post, means on said rocking member and said post to indicate the angular relation thereof, the upper end of said post having a pin disposed transversely thereof, a work support having a pair of apertured legs to receive said pin, means to lock said work support to said pin, and means on said pin and said work support to indicate the angular relation thereof.

16. In a work shaping apparatus having a spindle and a work shaping means carried by said spindle, a carriage movable in a direction parallel to the axis of said spindle, a rock member, bearing means on said carriage to support said member for rocking movement, a post, said rock member having a socket for pivotally supporting said post, the upper end of said post having a pin disposed transversely thereof, a work support having a pair of apertured legs to receive said pin, and means to lock said work support to said pin.
